UNITED STATES PATENT OFFICE.

JOHN ELWOOD BRYANS, OF WINNIPEG, MANITOBA, CANADA.

AUTOMOBILE-RADIATOR.

1,341,165.

Specification of Letters Patent.

Patented May 25, 1920.

Application filed April 9, 1919. Serial No. 288,737.

To all whom it may concern:

Be it known that I, JOHN ELWOOD BRYANS, of the city of Winnipeg, in the Province of Manitoba, Canada, have invented certain new and useful Improvements in Automobile-Radiators, of which the following is the specification.

The invention relates to improvements in automobile radiators, particularly heavy duty radiators, and the principal object of the invention is to construct a radiator which will not have any soldered joints, thereby dispensing with the many difficulties customarily experienced through breakage and the difficulties which such common construction gives when making repairs.

A further object of the invention is to construct the radiator from interchangeable parts, whereby the same can be readily assembled and repairs easily made and in such construction to utilize radiator tubes connected to the top and bottom tank by a special non-leak joint which not only permits of the ready insertion of the tube but also of the removal of the same.

A still further object is to construct the radiator in what might be termed tube sections to permit of the removal of a tube section without interfering with the remainder of the radiator.

With the above general objects in view the invention consists essentially in the arrangement and construction of parts hereinafter more particularly described and later pointed out in the appended claims, reference being had to the accompanying drawing in which:—

Figure 1 represents a front view of the radiator.

40 Fig. 2 represents a vertical sectional view through the radiator at X—X' Fig. 1.

Fig. 3 represents an enlarged detailed vertical sectional view through a portion of the radiator.

45 Fig. 4 represents a horizontal sectional view through a portion of the radiator.

Fig. 5 represents an enlarged detailed vertical sectional view through the joint connecting a tube to the tank.

50 In the drawing like characters of reference indicate corresponding parts in the several figures.

1 represents an automobile radiator presenting a top tank 2 and a bottom tank 3 which tanks are united by means of the

radiator side supports 4 and 5. 6 represents the customary inlet pipe to the bottom tank and 7 the outlet pipe from the top tank, it being here understood that the circulating waters pass to the radiator through the pipe 60 6 and out of the same through the pipe 7.

According to my invention I prefer to have access to the interior of the tanks for a reason later disclosed and in the present instance I have shown these tanks as fitted 65 with removable front plates 8 and 9, such plates being detachably fastened as by removable screws 10 to the tanks. It is here also to be understood that a water-tight joint is made when the plates are finally 70 screwed into position. The top and bottom tanks are connected by means of a plurality of similar tubular radiating tubes 11 which, owing to requirements, have to present comparatively thin walls. The tubes are all 75 similarly connected or jointed to the tanks at the top and bottom ends and I prefer to arrange them in sets, there being in the present case five tubes in a set, running from the front to the back of the radiator. There 80 can be however as many sets of tubes as occasion may demand. Each set of tubes appear between similar top and bottom base plates 12 and 13, the base plates being rectangular (see Fig. 4) and of a length equal 85 to the depth of the radiator from front to back.

Each base plate is fitted with a number of spaced facial projections or bosses 14 and the said base plates are bored out an equal 90 distance in from the rear side as indicated at 15 and interiorly screw threaded, the holes so formed communicating with second openings 16 of smaller diameter passing through to the front.

95 The radiator tubes 11 of each set are arranged with their upper and lower ends passing through the openings 16 of the top and bottom base plates and into the openings 15 and once inserted they are held 100 securely in place by applying exteriorly screw threaded jam sleeves 17 into the openings 15 and screwing them up against inserted packings 18 located around the ends of the tubes and at the inner ends of the sleeves. 105

The above arrangement connects in the present instance the five tubes of a set to the top and bottom plates but in the assembling of the radiator the jam sleeves 17 serve the further purpose of fastening the tube sec- 110

tions in place between the tanks and this is done by providing screw threaded openings indicated at 19 and 20 in the top plate 3' of the bottom tank and in the bottom plate 2' 5 of the top tank and screwing the jam screws through these openings and into their final positions within the openings 15.

The exposed ends of the jam screws are cross slotted at 21 to allow of the ready 10 application of a tool such as a screw-driver and in the assembled radiator access is had to the jam screws by removing the front plates 8 and 9 as occasion demands.

When the radiator is finally assembled in 15 accordance with the above construction it will be apparent that the top and bottom tanks are connected by the tubes which open to the tanks through the open centers of the jam screws.

20 With this arrangement it will be apparent that it is a very easy matter for one to remove a damaged tube as he simply has to drain the radiator in the ordinary way and then remove the front plates to allow him to 25 get at the jam screws associated with the particular tube. A screw driver will release the jam screws and once they are released the damaged tube can be pulled out and a new one readily inserted.

30 If desired a whole section of tubes can be taken out without interfering with the remaining sections, this being done by removing the jam screws which fasten that particular tube section to the top and bottom 35 plates 3' and 2' of the tanks 3 and 2.

While I have described in detail the joint made between the tube and the base plate, it will be readily understood this could be

modified without departing from the spirit of the appended claims.

40

What I claim as my invention is:—

1. The combination with the upper and lower tanks of a radiator, of a plurality of upper and lower pairs of base plates bearing against the under face of the top tank and the top face of the bottom tank, radiator tubes extending between the tanks and with their upper and lower ends extending into the base plates, packings contained within the base plates and surrounding the ends of the tubes and jam sleeves screw-threaded through the tanks into the base plates and receiving the ends of the tubes and having their innermost ends engaging the packing strips. 45 50 55

2. In a radiator, the combination with top and bottom tanks, of removable plates allowing of entrance to the interior of the tanks, a plurality of upper and lower pairs of base plates bearing against the under face of the top tank and the top face of the bottom tank, radiator tubes extending between the tanks and with their upper and lower ends extending into the base plates, packings contained within the base plates and surrounding the ends of the tubes and jam sleeves screw-threaded through the tanks into the base plates and receiving the ends of the tubes and having their innermost ends engaging the packing strips. 60 65 70

Signed at Winnipeg, this 18th day of March, 1919.

JOHN ELWOOD BRYANS.
